UNITED STATES PATENT OFFICE.

BENJAMIN K. ALBRECHT, OF ROWAYTON, CONNECTICUT.

SEAM-DAMPENING MACHINE.

1,245,149.

Specification of Letters Patent.

Patented Nov. 6, 1917.

Application filed January 10, 1917. Serial No. 141,518.

To all whom it may concern:

Be it known that I, BENJAMIN K. ALBRECHT, citizen of the United States, residing at Rowayton, in the county of Fairfield 5 and State of Connecticut, have invented certain new and useful Improvements in Seam-Dampening Machines; and I do hereby declare the following to be a full, clear, and exact description of the invention, such as 10 will enable others skilled in the art to which it appertains to make and use the same.

My invention relates to improvements in machines for dampening the seams of collars preparatory to bending the flap.

15 Referring to the drawings:

Figure 1 represents a front elevation of the machine and broken view of the legs;

Fig. 2 is a detail sectional view of the driving pulley, gears and broken view of the 20 shafts;

Fig. 3 is a detail upper plan view of the water tank;

Fig. 4 is a detail broken front elevation of the tank;

25 Fig. 5 is a broken elevation of the starting lever, rear end view of the pulley hub, one of the gear hubs and end of the driving shaft;

Fig. 6 is a broken upper plan view of the 30 machine bed, broken view of the tank supporting arms, and a plan view of the several parts of the operative mechanism;

Fig. 7 represents a side elevation of the 35 feed rolls, side elevation of one of the guide rolls, broken sectional view of the upper surface or table part of the bed, and guiding mechanism for the tab of the collar adapted to operate when the guide rolls are out of contact with the seam of the collar;

40 Fig. 8 is a broken view of the bed of the machine, a view of the bottom of the top feed roll, guide for the tab of the collar, and mechanism for actuating the seam located on the underside of the bed;

45 Fig. 9 is an enlarged sectional view of the guide rolls, enlarged view of their supporting rod, and sectional view of the hub in which the rod is mounted;

50 Fig. 10 is an enlarged broken sectional view of the floor of the water tank and delivery spout, also a modified construction for actuating the valve from the upper feed roll;

Fig. 11 is a broken view of a collar showing the operative position of the feed wheels 55 and guide rolls with respect to the collar during the dampening process; and

Fig. 12 is a broken view of a collar after leaving the guide rolls and where the collar is guided through the feed rolls by means 60 of a finger projecting from beneath the upper surface of the bed.

The feed roll shafts 1 and 2 carry the feed rolls 3 and 4 located with respect to the machine bed 5 as shown in Fig. 7. The 65 shaft 1 carries the gear 6, Fig. 2, to mesh with the gear 7 on shaft 2. 8 is the continuous running driving pulley whose hub 9, Fig. 5, is rotatively mounted on the hub 10 of the gear 6. This pulley is cupped 70 out to embrace and protect the gears which would otherwise be exposed and an accident liable to result thereby. Motion is communicated from the pulley to the shafts by forcing the pulley against the intermediary 75 friction washer 11, Fig. 2. This force is effected by means of the starting lever 12 with its lower end pivoted to the arm 13 and its intermediate portion embracing the hub of the pulley with the pins 14, Fig. 5, engaging 80 the slot 15 formed in said hub as shown in Fig. 2. 16 is a spring catch adapted to lock the lever in its advanced operative position.

The shaft 2 has also a vertical movement or adjustment to adjust the distance between 85 the feed rolls by reason of its passing through the block 17, Figs. 1 and 6, whose journals 18 are mounted to rock in the standard 19 secured to the machine bed. 20 is a bar secured by one end to said block 90 and by the opposite end to the fixed collar 21 on the shaft 2. This bar carries the adjustable weight 22 adapted to exert a pressure of the feed roll 3 on the collar proportionate to the position it occupies on the bar. 95 The bracket 23, mounted on the standard 19, carries the adjusting screw 24 engaging the outer end of bar 20 to tilt the shaft 2 and adjust the position of the feed roll 3 with respect to the lower feed roll 4.

25 is a sleeve journaled on the inner end of the shaft 2 and 26 is an arm projecting therefrom and it carries the guide roll mechanism comprising the hub 27 having the uprights 28 having the inner projections 29 105 adapted to register with grooves formed in

the arm 26,—one of said grooves, 30, is shown in Fig. 7,—whereby the position of said hub is adjusted on said arm and is secured in any of its adjusted positions by the 5 screw 31, Figs. 1 and 6.

32 is a rod adjustably mounted in the hub 27 carrying the guide rolls 33 and 34. The roll 33, Fig. 9, is rotatably secured to the end of rod 32 by the screw 35. The roll 10 34 has the hub 36 rotatably mounted on said rod and is backed up by the spring 37 for the purpose presently to be more fully explained.

38 is a water tank mounted on the support 15 39 and said support is rotatably mounted on the arm 40, which arm is adjustably mounted on the arm 41 by means of the slot 42 and screw 43, Fig. 6. 44 is a screw passing through a threaded hole in the lower 20 arm 41 and also through a central threaded hole in the busing 45 and contacts with the bottom of the standard 46 and thus adjusts the height of the water tank when the screw 47 is loosened, and, at the same time, the 25 water tank can be horizontally adjusted or swung to one side.

48 is a rod whose upper end is pivotally connected to the lever 49 pivotally supported on the forked stud 50, Fig. 3, on top of 30 the tank. The opposite end of this lever is pivotally supported in the upper forked end of the vertical rod 51 within the tank whose lower end is pivotally supported on one end of the lever 52, Fig. 4, pivotally mounted on 35 the forked stud 53. This lever carries the valve 54 covering the opening to the discharge spout 55 of the tank. The free end of the rod 48, Fig. 1, carries the pin 56 adapted to be engaged by the arm 30 when 40 a collar is inserted under the guide rolls 33—34, and thus lift the valve 54 within the tank and permit the water to be discharged on the upper feed roll 3. The height of the pin from the arm 30 can be adjusted for 45 different thicknesses of collars by means of the set screw 57. The same lifting effect of the valve is produced in the modified construction shown in Fig. 10 where the lower stem 58 of the valve carries the small wheel 59 in close proximity to the upper feed roll so that, when a collar is inserted between the 50 feed rolls, the valve is opened by the contact of the feed roll with the wheel 59. The upper stem 58^a is guided in the bracket 58^b.

55 60 is depressible plate operatively located in the opening 61, Figs. 6, 8, 11 and 12, of the bed and normally located above the same—Figs. 7 and 8—by the spring 62, and is temporarily retained thereby, its bar connection 60 63 contacting with the underside of the bed. The outer part of the plate 60 is journaled on the rod 64 secured in the studs 65 on the underside of the bed. 66 is a rod attached to the bar 63 whose upturned portion 67

forms a guide finger—presently to be more 65 fully explained, and it projects through the opening 68 of the bed and normally above the same, and is held in any of its laterally adjusted positions by the screw 69.

Referring to Fig. 11, the collar consists of 70 two parts, viz.: the flap 70 and the band 71. The former inserted into the latter which produces the raised seam edge 72 in connection with the well defined edge 73. After the collar is starched and ironed, it is necessary to dampen the flap along the edge 73 before it can be turned over and remain in a proper turned over condition. The water softens the starch sufficient to enable this to be done. If too much water is used it will 80 spread out beyond the bending point and destroy the gloss or finish previously imparted to the collar. If insufficient water is used, or the water is not applied to the upper feed before said roll contacts with the collar, the 85 starch is simply broken up due to lack of moisture.

By means of the arrangement of the mechanism previously described, I am not only able to regulate the supply of water in an 90 amount required for different thicknesses of collars, but also to have the water applied to the upper feed roll before the collar contacts therewith. As the collar is first entered at the guide rolls, the valve is raised and the 95 entire surface of the upper feed roll is thoroughly covered with water before the collar enters the feed rolls. Therefore, the preferred arrangement for actuating the water supply is from the guide roll arm rather 100 than from the upper feed roll as shown in Fig. 10. As the collars are passed rapidly through the machine, it is evident that when the valve is actuated by the insertion of the collar between the feed rolls it will have advanced a considerable distance before the water can reach the surface of the collar. While on the other hand, as before mentioned, the valve is actuated in advance of the entrance of the collar between the feed 110 rolls by the arm 26.

When the collar has advanced clear of the guide rolls, Fig. 12, the plate 60 is released to bring the guide finger above the bed and against the edge 74 of the tab 75 to maintain the seam of the collar against the face 115 of the upper feed roll until the collar is clear of the feed rolls.

To effect the required working pressure of the guide rolls against the collar, the friction washer 76, Figs. 1 and 6, is placed between the adjusting screw 77 and the outer end of the sleeve 25.

The swinging cover 78 covers an opening—not shown—in the top of the tank for the 125 admission of water.

In practice the position of the guide rolls with respect to the feed rolls and collar will

be such that the valve in the tank will be open during the entire time that the feed rolls are in contact with the collar.

Having thus described my invention, what I claim is:—

- 5 1. A seam dampening machine comprising two parallel feed roll shafts, gears connecting the shafts, a continuously running driving pulley rotatably mounted on the hub of one of the gears with its rim embracing the gears, and means for bringing the pulley in frictional driving engagement with the gear on whose hub the pulley is mounted.
- 10 2. A seam dampening machine comprising an upper and lower feed roll shaft, means for rotating said shafts, a sleeve journaled on the upper shaft having an arm projecting therefrom, guide roll mechanism adjustably mounted on the arm, an overlying water tank 20 having a delivery nozzle or outlet overlying

the upper feed roll, a valve above the outlet, and means connecting the valve with said arm so that said valve is raised when a collar is inserted under the guide rolls and water supplied to the upper feed roll before 25 said feed roll engages the collar and during the engagement of said feed roll with the collar.

3. A seam dampening machine comprising upper and lower shafts, feed rolls on said shafts, a sleeve journaled on the upper shaft having an arm projecting therefrom, a hub adjustably mounted on said arm and in advance of the feed rolls, a rod adjustably mounted in the hub, independently operating guide rolls rotatably mounted on said rod and under spring tension to accommodate for different width of seams.

In testimony whereof I affix my signature.
BENJAMIN K. ALBRECHT.
